Des. 232,605
Patented Sept. 3, 1974

232,605

DISPLAY CABINET

Cecil W. Spicer, 1408 California St. NE.,
Minneapolis, Minn. 55413

Filed Aug. 9, 1972, Ser. No. 278,964

Term of patent 14 years

Int. Cl. D6—04

U.S. Cl. D6—25

FIG. 1 is a front elevational view of the display cabinet, the sides and rear being symmetrical;

FIG. 2 is a top plan view of the display cabinet;

FIG. 3 is a sectional view of the display cabinet taken along the line 3—3 of FIG. 1; and

FIG. 4 is a sectional view of the display cabinet taken along the line 4—4 of FIG. 1.

I claim:

The ornamental design for a display cabinet, substantially as shown and described.
